UNITED STATES PATENT OFFICE.

RALPH SIMPSON KELSO, OF CHICAGO, ILLINOIS, ASSIGNOR TO THE STANDARD SEWING MACHINE COMPANY, OF CLEVELAND, OHIO, A CORPORATION OF OHIO.

SEWING-MACHINE.

1,176,461.

Specification of Letters Patent. Patented Mar. 21, 1916.

Original application filed June 30, 1911, Serial No. 636,138. Patent No. 1,129,403, dated February 23, 1915.
Divided and this application filed November 17, 1914. Serial No. 872,527.

To all whom it may concern:

Be it known that I, RALPH S. KELSO, a citizen of the United States, and resident of Chicago, in the county of Cook and State 5 of Illinois, have invented certain new and useful Improvements in Sewing-Machines, of which the following is a specification.

This invention relates to sewing machines, and is a division of the application which 10 resulted in my prior Patent, No. 1,129,403, of February 23, 1915. The present application relates particularly to the edge gage mechanism and the presser mechanism disclosed, but not claimed, in the co-pending 15 application referred to.

The principal object of the present invention is to provide gaging and pressing means so associated that in the normal operation of the machine, the gaging means will rise 20 and fall substantially in unison with the presser, though mounted independently of the presser and capable of independent movement relative to it when it is desired to throw the gage into and out of action.

25 The invention is illustrated in the accompanying drawings, certain views of which illustrate the trimming mechanism constituting the subject matter of the above-named pending application to show the relation between the mechanism of the present application and said trimming mechanism.

In the drawings:—Figure 1 is an elevation of the front side of a portion of the 35 head of a sewing machine illustrating the present invention applied thereto, only so much of the sewing machine being shown as is necessary for illustration of the invention; Fig. 2 is a vertical section taken on the line 2—2 of Fig. 1 and looking in the 40 direction of the arrows; Fig. 3 is a broken elevation of the rear side of the mechanism shown in Fig. 1, the trimming mechanism being omitted to more clearly illustrate the 45 operation of the presser and edge gage mechanism; Fig. 4 is a broken elevation corresponding to Fig. 1 showing the position which the parts assume when the presser bar is in its raised position; and 50 Figs. 5 and 6 are detail views illustrating the edge gage and the means for throwing it into and out of action and for holding it out of action.

Figs. 1, 2 and 4 illustrate the trimming

mechanism which constitutes no part of the 55 present invention, and, therefore, a detailed description thereof is not necessary. For the present purposes, it is only necessary to note the stationary bracket *a* secured to the under side of the head of the sewing machine, and the lever *b* pivoted thereto and to a reciprocating knife bar *c*. The frame which carries the lever *b* has pivotally associated therewith, the movable knife *d* which is yieldingly held in proper relation 60 to said frame by a suitable spring *e*. By this construction, the reciprocation of the knife bar *c* imparts a curvilinear movement 65 of the movable knife *d* in the manner described in the above-mentioned co-pending 70 application.

In connection with the trimming mechanism just described, it is customary to employ suitable pressing means for engaging the work close to the line of stitching. In 75 the present instance, the preferred construction is a roller presser of the type described in detail and claimed in my prior Patent No. 1,129,404, of February 23, 1915.

The main features of this part of the 80 machine are the roller presser 1 and suitable means for adjusting it in two intersecting paths, preferably in a horizontal plane, and for also moving it into and out of an operative position, the construction being such 85 that when the roller presser is moved to its inoperative position, it is located at a considerable distance from the needle and the knife *d*, and the operator has ready access to the needle for threading it and to the 90 knife for adjusting it, etc. Here, said roller presser is shown as carried by an arm 2, which is pivoted on a horizontally adjustable member or carrier 3 secured to a block 4, fastened to the lower end of the presser 95 bar 5 (Fig. 3). The presser or roller 1, being connected to the usual presser bar 5 through the intermediary of the arm 2 and cross piece 3, moves up and down with the presser bar 5 upon actuation of the usual 100 lever 6 controlling the movements of the presser bar.

Associated with the presser is also shown an edge gage at 7. The working portion of the gage proper of this edge gage is here 105 illustrated as an extension of a spindle 8 mounted in a relatively long bearing 9, which, in the present construction, is ad-

justably secured to the same bracket *a* to which the lever *b* of the trimming mechanism is pivoted. The bracket *a* is illustrated as having an open-sided clamp 10 formed as a part of the bracket *a*, and so constructed as to permit the gage carrier, that is the sleeve of the spindle, to be located in an inclined or diagonal position with respect to the line of stitching. The spindle 8 has a stop 11, between which and the lower end 10 of the bearing 9, is shown a spring 12, which normally holds the edge gage down and in working position. At the upper end of said sleeve is shown a lateral arm 13, with which 15 coöperates a detent device 14 carried by the upper end of the spindle 8. This detent may be of any suitable construction, one simple form being clearly illustrated in Figs. 5 and 6. By means of the latch arm 15 of this detent, the spindle may be latched in its uppermost position, shown in said 20 figures, or released when it will be drawn down by the spring 12 to the full-line position, shown in Fig. 5. This control of the throwing in and out of the edge gage is entirely independent of any control by the other mechanism. Adjustable means may be provided, if so desired, for limiting the downward movement of the edge gage, such 25 means, in the present instance, taking the form of a thumb screw 16', which is threaded in the detent device 14, and contacts with the lateral arm 13, in the lowermost position of the edge gage. A suitable lock-nut 17 may be provided for locking the thumb screw 16' with respect to the detent 30 35 14.

An important feature of the mechanism, however, is the provision of means for controlling the throwing out of action of the edge gage directly from the pressing means. It is desirable to raise the edge gage at the same time that the presser is raised, and in order to accomplish this result, there is illustrated, at 40 45 50 55 60 65 16, an upwardly extending arm secured to the block 4, which arm has, at its extreme upper end, a finger that projects under the main portion of the detent device 14 and engages the under side of it at a point close to the spindle 8, as best shown in Figs. 1 and 4. Thus, it will be clear that whenever the lever 6 is actuated to raise the presser bar and presser, the edge gage will also be raised simultaneously with the presser mechanism by the action of the arm 16, which engages and lifts the detent 14 and with it, the edge gage. The relative positions of these parts, when in contact with the work and when raised away from the work, are clearly shown in Figs. 1 and 4.

By the foregoing construction, it will be seen that the edge gage may be raised at any time independently of the presser mechanism, and may be supported in its raised 65 position by means of the latch device de-

scribed. However, when the presser bar is raised by the lever 6, the arm 16, which rises in unison with the presser bar, acts upon the edge gage to shift the same to its raised position. When the presser bar is lowered, 70 the spring 12 serves to return the edge gage to its operative position, as the upward movement of the presser bar is not sufficient to cause the latch device to operate. It is only when the edge gage is raised a sufficient distance independently of the presser bar that the latch device operates to hold the edge gage in its raised position until the latch device is so actuated as to release the 75 80 85 90 95 100 105 110 115 120 125 130 135 140 145 150 155 160 165 170 175 180 185 190 195 198 200 205 210 215 220 225 230 235 240 245 250 255 260 265 270 275 280 285 5. In a sewing machine, the combination with a presser-bar and presser, of an edge-gage mounted independently of the presser-bar for longitudinal sliding movements, 5 means to yieldingly hold said gage in its operative position, means to permit raising of said gage independently of the presser-bar, means to hold it in its raised position, and means whereby the gage is raised when 10 the presser-bar is raised.

6. In a sewing machine, the combination with a presser-bar and presser, of an edge gage, a bearing disposed adjacent to the

presser-bar and in which the edge gage is 15 slidably mounted, and means associated with the presser-bar and engageable with a slide-able portion of the edge gage for raising the edge gage from the work on the rising of said presser-bar and presser.

Signed at Chicago, in the county of Cook, 20 and State of Illinois, this 13th day of No-
vember, A. D. 1914.

RALPH SIMPSON KELSO.
